GARMENT HANGER

John P. Brown, Brooklyn, N. Y.

Application December 8, 1945, Serial No. 633,587

15 Claims. (Cl. 223—91)

1

The invention relates to a hanger from which articles may be hung and particularly relates to a garment hanger. Garment hangers as heretofore constructed provide a frame upon which a coat or dress may be hung and a simple bar over which trousers or a skirt can be hung. These frequently slip off of the bar and are not wholly satisfactory.

It is an object of the invention to construct a new and novel hanger which clamps the article or garment to the hanger by the weight of the article and provides a wide clearance or space for inserting and removing the garment.

A further object is to construct a clamping hanger having a double movement, one to open the clamping means widely for easy insertion of an article to be hung and a clamping movement or pivoting which utilizes the weight of the article to clamp the same.

Another object of the invention is to construct a hanger having two clamp members or bars one of which is movable away from the other to provide a wide space or clearance between the bars for the insertion of a garment and the other pivots to obtain a clamping action between the bars.

Another object of the invention is to provide parts so that an existing hanger can be converted to the hanger of the invention having a holding bar and a clamping bar, the former being movable away from the other and the clamping bar clamping the garment to the hanger by the weight of the garment.

Other objects of the invention will be more apparent from the following description taken in connection with the accompanying drawings showing preferred embodiments of the invention in which:

Figure 1 is a plan view of a garment hanger having the clamping action.

Figure 2 is a cross section taken on line 2—2 of Figure 1.

Figure 3 is a cross section through a hanger in which the holding bar is a stationary member and the clamping bar is both pivoted for clamping action and mounted for movement away from the fixed holding bar.

Figure 4 shows a garment hanger of the conventional type which has been modified to provide a clamping type of garment hanger.

The hanger has general application but is designed primarily as a garment hanger. The hanger includes a frame 10 which for a garment hanger will have any suitable coat hanger shape. A hook 11 may be provided for suspending the

2

hanger and any garment carried thereby from a clothes bar. The frame carries a movable holding bar means 14. It may be movable in any direction, the movement preferred however, is a movement parallel with the frame which is obtained by suspending the holding bar from a pair of spaced links 15 having an eye 16 in the end thereof. The eye is received in a supporting loop 17 of suitable construction carried by the frame. A staple may form the supporting loop. The holding bar means is pivotally mounted upon the frame to swing to a position as shown in dot dash lines in Figure 2 in which position a garment can easily be inserted or draped over a clamping bar means. The bar may have raised portions 18, if desired, to accommodate the holding bar for seams in the garment where the material is thicker.

Means is provided to retain the holding bar means in proper relation on a hanger when clamping a garment thereto. This means may take any suitable form, the simplest construction being to extend the ends 19 of the holding bar to form stops which engage the frame and thereby retain the holding bar in proper position for clamping a garment. The holding bar means and clamping bar means are in proper or cooperative clamping position when the holding bar is in the path of movement of a longitudinal edge of the clamping bar.

A clamping bar means 22 is supported upon pivots 23 located between its long edges which are carried by the frame 10 in the construction of Figure 1. The width of the clamping bar means and the location of the pivots with respect to the edges depends upon the leverage or clamping pressure desired to be developed by the weight of the garment. The clamping bar extends laterally so that one edge moves towards the holding bar 14 to clamp the garment between the bars. The other edge has a downward force applied thereto, indicated by the arrow, caused by the weight of the garment hanging over the clamping bar. The clamping bar may have suitable stop means to prevent it from making a complete rotation. The simplest construction of stop means is to extend the ends 24 of the bar which engage the frame and thereby prevent rotation of the bar although permitting ample pivoting for clamping action upon a garment or article draped over the clamping bar.

The garment hanger is operated by tilting the hanger frame 10 horizontally so that the holding bar 14 hangs downwardly or in open position. In this position the holding bar means and the

clamping bar means are widely separated from each other so that a garment G such as a pair of pants can be easily inserted therebetween. Tilting the hanger frame to a vertical position swings the holding bar means downwardly to the position shown in Figure 2 where it is adjacent to an edge of the clamping bar means. The garment or trousers may then be released and its weight pulls one edge of the clamping bar downwardly thereby raising the opposite edge to clamp the garment between the holding bar means and the clamping bar means.

In the construction of Figure 3 the wide separation between the clamping bar means and the holding bar means is secured in another manner. A frame 28 may have the usual hook 29 for supporting the hanger from a clothes bar. The frame carries a holding bar means 30 which is fixed to the frame.

A clamping bar means 33 is carried upon pivots 34 and is comparable in construction to the clamping bar of Figure 1 in that it is relatively wide so that a clamping leverage is secured. The clamping bar likewise extends in a lateral direction when clamping a garment thereto. The hanger of Figure 3 differs from that of Figures 1 and 2 in that the clamping bar is movable towards and away from the fixed holding bar means. This motion is accomplished by mounting the pivots at each end of the clamping bar means upon a lever 35 at each end of the bar. Each lever 35 is mounted upon a pivot 36 carried by the frame. In this construction the clamping bar means not only has a pivotal movement for clamping action but it also is mounted to move towards and away from the holding bar 30 so that a garment may be easily draped over the clamping bar. When the clamping bar with the garment thereon has been swung up to the position shown in Figure 3, the weight of the garment pulls downwardly in the direction of the arrow on one edge of the clamping bar which brings the opposite edge thereof into clamping contact with the garment to clamp the same between the clamping bar means and the holding bar means 30.

The levers 35 preferably extend far enough so that the ends thereof engage the holding bar means and serve as a stop or stop means for retaining the clamping bar means in clamping position in which the holding bar means is in the path of movement of a longitudinal edge of the clamping bar means. The weight of the garment will normally retain the levers in contact with the holding bar means. In order to doubly assure the retention of the levers against the holding bar means a spring clip 38 may be provided which snaps beneath the holding bar means and releasably retains the levers and hence the clamping bar means in clamping position with respect to the holding bar means.

It is not necessary that a complete hanger be built in order to practice the invention. In Figure 4 a construction is illustrated by which a conventional hanger may be converted to a clamping hanger. The hanger includes a frame 41 which carries a bar 42 fixed thereto. A holding bar means 43 has links 44 with an eye 45 on the end thereof each of which is received in a loop 46 which may be a staple driven into the edge of the frame. This provides pivotal mounting for the holding bar means which enables the latter to swing to and from clamping position in order to provide a wide opening between the latter and the clamping bar means. The ends 47 of the holding bar means may extend upwardly to en-

gage the frame and thereby retain the holding bar means in clamping position.

The clamping bar means 50 is similar to the clamping bar means 22 and 33 of Figures 1 and 5 in that it is relatively wide in order to provide a clamping leverage and extends laterally with respect to the frame. The clamping bar means may be pivotally carried by the fixed bar 42 by any suitable means including a pair of bearing 10 members 51 which are secured to the clamping bar and permit the latter to pivot on the fixed bar 42. The clamping action in this construction is like that of Figures 1 through 3 and need not be described in detail. Here again the weight 15 of the garment rotates the clamping bar to bring one edge thereof towards the holding bar and thereby exert clamping pressure upon the garment or article between the two bar or bar means so that the garment will be clamped therebetween and will not slide off the hanger.

It will be observed that the hangers described embody two movements, one movement which is a separation movement to bring the two bars away from each other so that a garment may be readily inserted or removed therebetween. The separation movement is a swinging or pivotal movement essentially parallel to the frame although it is clear that clearance or separation may be secured by a lateral swinging of the holding bar. The 25 second movement is a pivoting action of the clamping bar means which utilizes the weight of the garment applied at one longitudinal edge thereof to turn the clamp bar means and move the other longitudinal edge towards the holding 30 bar means whereby the garment is clamped between the two bars.

This invention is presented to fill a need for improvements in a hanger. It is understood that various modifications in structure, as well as 40 changes in mode of operation, assembly, and manner of use, may and often do occur to those skilled in the art, especially after benefiting from the teachings of an invention. Hence, it will be understood that this disclosure is illustrative of 45 preferred means of embodying the invention in useful form by explaining the construction, operation and advantages thereof.

What is claimed is:

1. A garment hanger comprising a frame, a holding bar means, a flat clamping bar means extending laterally with respect to the frame and having a width to provide longitudinally extending edges for clamping pressure between one longitudinal edge thereof and the holding bar means by the downward weight applied at the other longitudinal edge thereof by an article hanging thereover, pivot means between the longitudinal edges of the clamping bar means for pivotally mounting the same, and means supporting one of the bar means upon the frame in the path of movement of a longitudinal edge of the clamping bar means and to move the same away from the other bar means to permit wide separation between the two bar means and thereby enable the article to be easily inserted therebetween and draped over the clamping bar means and thereafter to be returned to its position with the holding bar means cooperatively adjacent to the longitudinal edge of the clamping bar means for clamping action therebetween.
2. A garment hanger comprising a frame, a holding bar means, a flat clamping bar means extending laterally with respect to the frame and having a width to provide longitudinally extending edges for clamping pressure between one

longitudinal edge thereof and the holding bar means by the downward weight applied at the other longitudinal edge thereof by an article hanging thereover, pivot means between the longitudinal edges of the clamping bar means for pivotally mounting the same, and a pivot structure supporting one of the bar means upon the frame in a position in which the holding bar means is in the path of movement of a longitudinal edge of the clamping bar means and upon pivot means spaced from the bar means to swing the same away from the other bar means to permit wide separation therebetween and thereby enable the article to be easily inserted therebetween and draped over the clamping bar means and thereafter to be returned to a position where the holding bar means is cooperatively adjacent to the longitudinal edge of the clamping bar means for clamping action therebetween.

3. A garment hanger as in claim 2 including means retaining the pivot structure in clamping position with the holding bar means adjacent a longitudinal edge of the clamping bar means.

4. A garment hanger as in claim 2 including stop means to obstruct the clamping bar means against complete rotation.

5. A garment hanger as in claim 2 including extensions upon at least one end of the clamping bar means to form stop means to obstruct the same against complete rotation.

6. A garment hanger comprising a frame, a holding bar means, a flat clamping bar means extending laterally with respect to the frame and having a width to provide longitudinally extending edges for clamping pressure between one longitudinal edge thereof and the holding bar means by the downward weight applied at the other longitudinal edge thereof by an article hanging thereover, pivot means between the longitudinal edges of the clamping bar means and received by the frame for pivotally mounting the same to the frame, and means supporting the holding bar means upon the frame and in the path of movement of a longitudinal edge of the clamping bar means and to move the holding bar means away from the clamping bar means to permit wide separation between the bar means and thereby enable the article to be easily inserted therebetween and draped over the clamping bar means and thereafter to be returned to a position where the holding bar means is cooperatively adjacent to the longitudinal edge of the clamping bar means for clamping action therebetween.

7. A garment hanger as in claim 6 including stop means to limit the rotation of the clamping bar means.

8. A garment hanger as in claim 6 including pivots for the supporting means spaced from the holding bar means to pivotally support the same upon the frame and to swing the holding bar means with a parallel movement towards and away from the clamping bar means, and stop means for retaining the holding bar means in a position adjacent a longitudinal edge of the clamping bar means.

9. A garment hanger as in claim 6 including pivots for the supporting means spaced from the holding bar means to pivotally support the same upon the frame and to swing the holding bar means with a parallel movement towards and away from the clamping bar means, and the ends of the holding bar means extending into engagement with the frame to retain the same adjacent to a longitudinal edge of the clamping bar means.

10. A garment hanger as in claim 6 including pivots for the supporting means spaced from the holding bar means to pivotally support the same upon the frame and to swing the holding bar means with a parallel movement towards and away from the clamping bar means, stop means for retaining the holding bar means in a position adjacent the edge of the clamping bar means, and stop means to limit the rotation of the clamping bar means.

11. A garment hanger comprising a frame, a holding bar fixed to the frame, a flat clamping bar extending laterally with respect to the frame and having a width to provide longitudinally extending edges for clamping pressure between one longitudinal edge thereof and the holding bar by the downward weight applied at the other longitudinal edge thereof of an article hanging thereover, pivot means between the longitudinal edges of the clamping bar for pivotally mounting the same, and pivot structure mounting the clamping bar upon the frame parallel to the holding bar and in a position in which the holding bar is in the path of movement of a longitudinal edge of the clamping bar and having pivots spaced from the clamping bar and received by the frame to swing the clamping bar away from the holding bar to permit wide separation between the two bars and thereby enable the article to be easily inserted therebetween and draped over the clamping bar and thereafter to be returned to its position with the holding bar means cooperatively adjacent to a longitudinal edge of the clamping bar means.

12. A garment hanger as in claim 11 including stop means limiting the movement of the pivot structure to a position where a longitudinal edge of the clamping bar is in cooperating relation adjacent to the holding bar.

13. A garment hanger as in claim 12 including stop means to obstruct the clamping bar against complete rotation.

14. A garment hanger conversion unit for converting a frame having a fixed bar carried thereby into a clamping hanger comprising a holding bar, a flat clamping bar having a width to provide longitudinal edges one of which provides clamping pressure between it and the holding bar by the weight of an article hanging thereover and applied at the other longitudinal edge, a pivot structure connected with the holding bar and having pivot means spaced from the holding bar and adapted to be secured to a hanger frame to support the holding bar in the path of movement of a longitudinal edge of the clamping bar and to swing the holding bar away from the clamping bar to permit separation of the same and thereby enable an article to be easily draped over the clamping bar and thereafter to swing to a position where the bars are adjacent to each other for clamping action upon the article, pivot means for pivotally securing the clamping bar upon the fixed bar of a frame, and stop means limiting the swinging movement of the holding bar to a position in the path of movement of a longitudinal edge of the clamping bar.

15. A garment hanger converted to a clamping hanger comprising a frame having a fixed bar carried thereby, a holding bar, a flat clamping bar having a width to provide longitudinal edges one of which provides clamping pressure between it and the holding bar by the weight of an article hanging thereover and applied at the other longitudinal edge, pivot means for pivotally securing the clamping bar upon the fixed bar of a

frame, a pivot structure connected with the holding bar and having pivot means spaced from the holding bar secured to the hanger frame to support the holding bar in the path of movement of a longitudinal edge of the clamping bar and to swing the holding bar away from the clamping bar to permit separation of the same and thereby enable an article to be easily draped over the clamping bar and thereafter to swing to a position where the bars are adjacent to each other 10 for clamping action upon the article, and stop means limiting the swinging movement of the holding bar to a position in the path of movement of a longitudinal edge of the clamping bar.
